STENCILING APPARATUS

Ernest M. Hommel, Pittsburgh, Pa., assignor to
 The O. Hommel Company, a corporation of
 Pennsylvania

Application August 28, 1934, Serial No. 741,762

14 Claims. (Cl. 101—125)

This application comprises a continuation in part of application Serial No. 666,458, filed April 17, 1933.

My invention relates to apparatus for the application of characters and designed decorations upon bottles, jars and other objects. The invention is more particularly directed to apparatus for applying decorations of vitreous color material to an object of glass, so that the decoration may be vitrified and fused in the surface of the glass in accordance with well-known practice.

The object of the invention is to provide simplified apparatus of this sort, to the end that the application of such decorations may be more readily accomplished, and accomplished with greater accuracy. I aim especially at means of this kind for decorating a cylindrical or curved surface.

In the accompanying drawings Fig. I is a view in plan from above of apparatus embodying the invention; Fig. II is a view of the apparatus in cross-section, taken on the plane II—II, Fig. I, and shown to larger scale; Fig. III is a view taken at right angle to the view in Fig. II, and shows the apparatus partly in side elevation and partly in vertical medial section; Fig. IV is a view of the apparatus in side elevation, and indicates an alternative use; Fig. V is a view in plan, showing a modification in the pad element of the structure; Fig. VI is a view to smaller scale showing in cross-section a modification in the apparatus; Fig. VII is a longitudinal sectional view of the modified apparatus, taken on the plane VII—VII of Fig. VI; Fig. VIII is a longitudinal sectional view of another modification of the apparatus; and Figs. IX and X are views comparable with Figs. VI and VII, respectively, illustrating still another modification.

In accordance with the invention, I provide a pad 1 of felt, or of other suitable absorbent and elastic material. The pad 1 is set in a shallow pan 2, and its effective face 1a in this case is a flat face lying a substantial interval (approximately $\frac{1}{4}$ ") above the rim of the pan. The pad 1 is saturated with the vitreous material which is to be applied in predetermined pattern upon the object to be decorated—which object in this case is a cylindrical glass jar 3. The vitreous material comprises a vitrifiable pigment (or a pigment mixed with vitrifiable substance) carried by a liquid vehicle, such as balsam copaiba or dammar varnish. An oily pigment mixture of this nature readily adheres to a glass surface.

Immediately above the effective face 1a of the

pad, a screen 4 is supported, and in this case the screen consists of silk fabric drawn taut upon and secured (say by means of staples or tacks 5) to a rectangular frame 6 of wood. The frame 6 is so supported relatively to the pan 2 that the screen 4 extends at an interval of $\frac{1}{4}$ " above the face of the pad and in a plane parallel thereto. The screen may consist of a fine-mesh metal screen, or it may be a screen of fabric other than silk. In any case, the screen is flexible, to the end that an applied object may be pressed upon the pigment-saturated pad. Provision is made that the screen shall be impervious to liquid, save in the areas 7 which in the pattern of the decoration to be applied are allowed to remain pervious. This is accomplished, conveniently, by applying upon the upper face of the silk fabric a thin coating 8 of nitrocellulose lacquer, leaving only the patterned areas 7 uncoated. Alternately, the intended pattern may be cut in a thin sheet of suitable material, such as shellacked or waxed paper (or cardboard), and the resulting stencil may be applied to the face of the silk fabric. Again, it will be understood that, by means of well-known photographic processes, the predetermined design may be provided in a sensitized fabric which before photographic treatment is impervious, and after treatment is pervious only in the patterned areas (7).

In service the frame 6 is so located that the pervious areas 7 of the screen lie immediately over the effective face of the impregnated pad 1. It will be understood that the screen (4, 8) is drawn and maintained taut upon the frame 6, and in such taut condition the screen serves as a yielding support upon which the jar 3 may be rolled, conveniently under the palm of the hand. As the jar is so rolled across the screen, the screen yields downward (in the manner indicated at 9 in Fig. III) and is progressively pressed into contact with the face of the pad 1. Indeed, under the influence of the advancing jar the pad itself is compressed, and the vitreous pigment with which it is saturated is exuded through so much of the screen as is pervious and upon the surface of the jar. That is to say, as the jar is rolled across the pervious areas 7 of the screen, the sticky pigment material is squeezed through the screen, and is progressively picked up by the cylindrical face of the advancing jar, so that, upon traversing the pervious areas of the screen, the jar is decorated with the moist pigment material.

In case the design is a two-color design, one color is first applied and dried upon the object, and then the second color is applied; thereupon,

both applications of vitreous pigment having been dried thoroughly, the object is fired and the two-color decoration is vitrified. In such manner a plurality of colors may be successively applied; decorations of elaborate color schemes become practical, and the field of the artist is widened. Indeed, in many cases, I have found that two or more colors may be applied simultaneously.

The decoration illustrated in Fig. I affords an example. Let it be assumed that the character "A" is to appear in red within the circle, say of black. In such case I employ a pad which is modified in accordance with the structure shown in Fig. V. The modified pad comprises a plurality of pad elements 50 and 51; each pad element is impregnated with an oily mixture of vitreous pigment of distinct color, and each pad element is supported in its own pan or pan compartment. In the illustration the pad element 50, advantageously, is located in an inner pan compartment 52, while the pad 51 is held in an outer pan compartment 53. The inner pad 50 is impregnated with red pigment, and the outer pad 51 with black; the proportions of the pads are such that in service the pad 50 underlies the letter "A" in the screen 4, while the outer pad 51 underlies the encompassing circle. Accordingly, when the jar 3 is rolled across the screen, the design (1, 1) is applied to its surface in the desired red and black colors. In this manner designs of two or more colors may in one operation be applied to objects having a cylindrical or round surface.

While I am particularly concerned with the decoration of round objects, it should be noted that my apparatus may be employed with advantage in decorating flat objects. Suppose, for example, that the flat plate of glass 40, shown in Fig. IV, is to be decorated with the "circle A" design 1, 1 of Fig. I; it is merely necessary to lay the plate upon the screen, and to press it downward, as indicated by the arrow (Fig. IV). The vitreous paint may thus be applied in the desired pattern to the surface of plate 40. Of course, care must be exercised in the operation, to prevent lateral shifting of the plate and consequent smearing of the work.

In the pattern areas 1 the fabric of the screen 4 comprises fine open-work through which the decorating material is exuded; upon moving 50 through the interstices of such open-work the decorating material normally adheres to the surface of the glass object in the form of microscopic dots or islands, which lend to the applied decoration a suggestion of the open-work fabric through which the material was exuded. It has been discovered that this effect may be obviated by presenting an excess of decorating material on the face of the pad 1; that is, more than the usual or required amount of decorating material is made accessible upon the face of the pad—the pad may be considered to be not only saturated but "flooded" with decorating material. The consequence and effect of this so-called flooded supply of decorating material is that the microscopic islands or dots applied upon the surface of the object are overcharged with the liquid material, wherefore the islands merge or run together soon after application, and provide on the face of the object a smooth uninterrupted 65 film of decorating material in the desired pattern.

It has been discovered that, alternately, a rigid or semi-rigid surface bearing a heavy, flooded coating of the decorating material may be used 70 with good results. Referring to Figs. VI and

VII, a rigid platen 10 of metal, or of rigid or semi-rigid rubber, may be organized with the stencil screen 4. The top of the platen 10 presents an extended surface area which normally lies an interval from the taut screen 4; the surface of the platen is provided with a heavy coating 11 of decorating material. The article 3 is rolled across the stencil 4 in the manner already described, and the stencil yields (under the pressure of the object) from the plane of its extent 10 and into contact with liquid-bearing surface. And such contact is, in the case of the cylindrical article 3, a line contact which, during the rolling of the article 3, advances across the platen.

The body or quantity of decorating material 15 11 applied to the face of the platen is not such a thin film as is usually applied by an inking roller; it is a heavy film or layer of viscous material which is upwards of 1/64 of an inch or more in depth, and in the following claims I use the 20 word "flooded" as descriptive of the heavy application of viscous decorating material. Advantageously, an adequate coating may be obtained by immersing the surface of the platen 10 in a pool of the decorating material. Indeed, 25 I provide a reservoir 12 beneath the screen 4, and the platen is supported upon one or more plunger rods 13 which extend through packing glands 14 in the bottom of the reservoir. After each decorating operation, or less frequently 30 in some cases, the plungers 13 are lowered, bringing the face of the platen 10 beneath the surface S of the supply of decorating material in the reservoir 12; the liquid decorating material of the pool overflows the face of the platen, whereupon the platen is elevated again. A heavy coating or layer of decorating material remains upon the surface of the platen, and the decorating operation may go forward with the so-called excess quantity of decorating material cooperating 35 with the stencil screen.

Normally, the decorating material is a thick, viscous, or soupy fluid including vitrifiable solids in suspension. The thickness of the coating on the surface of the platen after immersion is relational to the viscosity of the fluid material, and I have found that by varying the proportions of the solids in the fluid material—varying the viscosity of the liquid in the reservoir—the depth of the coatings 11 successively applied to the platen may be regulated. Conveniently, an agitator 15 may be rotated to maintain the decorating mixture homogeneous.

In an alternative arrangement, the platen 10 is slideable in ways 16, as indicated in Fig. VIII; the supporting frame 6 of the stencil is recessed at 17, to permit the platen to be moved from its serviceable position (cf. the dotted lines 10a), beneath the stencil 4 to a position to one side, as shown in full lines 10. Over the course of movement 60 of the platen 10, a hopper 18 holds a store of decorating material; the hopper is provided with an elongate, narrow, discharge orifice 19, which extends transversely of the path of the platen; the orifice 19 is subject to the control of a gate 20 which is swung aside as the platen is drawn from beneath the screen 4, whereby a heavy, flooded coating 11 is applied to the surface of the platen. During the return movement of the platen, the gate 20 is closed, and a rubber squeegee 21 may 70 be organized to smooth out and distribute to uniform depth the decorating material applied during the outward travel of the platen.

In still another modification, an endless band 22 (Figs. IX and X) is mounted upon two spaced- 75

apart rollers 23 which are trunnioned in the opposite side walls of a reservoir 24, supported beneath the flexible stencil sheet 4. The upper reach of the band 22 extends flat upon a bed plate 25 secured rigidly upon cross bars 26, the relative positions of the parts being such that the upper face of the band lies an interval below the stencil screen. The band in its lower reach is immersed in the bath 28 of liquid decorating material in the reservoir 24, and suitable means are provided for causing the intermittent travel of the band. For purposes of illustration, I show the shaft of one roller 23 provided with a hand crank 27. Accordingly, the lower reach of the continuous band 22 may be caused to travel through the bath 28, whereby its lower surface is coated with the desired heavy, flooded layer of decorating material, and upon travelling upward around one of the rollers 23, the portion of the band leaving the bath moves into the upper reach, and presents its coated surface upward. Thus, a heavy layer of decorating material is provided over an extended area beneath the screen 4, and, travel of the band being intermittent, the article 3 is provided with decoration in the manner already described. And, after each decorating operation, or when the excess supply of decorating material on the upper surface of the band is depleted, the band is again shifted to bring a new expanse of decorating material into position of service.

I have found that in using my apparatus the vitreous pigment is applied in precise accordance with the predetermined pattern, and that no high degree of skill is required to provide a round or curved article with a nicely defined decoration. The moist pigment mixture thus applied to the article is allowed to dry, and then is fired in accordance with usual practice, whereby the decoration is vitrified and becomes an integral part of the article's glass surface. It is contemplated that the liquid vehicle (balsam copaiba, or dammar varnish) may be used without pigment or vitrifiable substance in my apparatus, and that such viscous liquid vehicle may be applied in pattern to the article to be decorated. Pigmented, vitrifiable substance in powdered form may then be dusted over the surface of the article, and so much of the surface as is coated with the liquid vehicle will retain the pigment material, whereupon drying and firing may proceed in the usual manner. To avoid prolixity in the following claims, the words "liquid vitrifiable material" are employed to cover the use of the vehicle alone, or the use of some liquid mixture which is treated after application, to provide the contemplated vitrifiable decoration.

I claim as my invention:

1. In apparatus for applying decoration upon an object, the combination of an elastic pad of absorbent material saturated with a pigmented liquid, a flexible stencil drawn taut and independently supported an interval from the effective face of said pad, said stencil being of substantially greater effective area or expanse than the area or expanse of said object to be decorated, and providing a yielding support adapted to give under pressure of said object into compressing engagement with said pad.

2. In apparatus for applying vitreous decoration upon an object, the combination of an elastic pad of absorbent material saturated with a vehicle adapted to carry pigmented vitreous material, a flexible stencil drawn taut and supported independently of and an interval from the effective face of said pad, said flexible stencil being of

substantially greater expanse than the face of said elastic pad, and providing a yielding support adapted to give under pressure of said object into compressing engagement with said pad.

3. Apparatus for use in applying a vitrifiable decoration upon an object, which apparatus includes in combination a container or pan having a shallow recess, an elastic pad of absorbent material positioned in said recess, said pad being saturated with a liquid vehicle carrying vitrifiable substance, a flexible stencil drawn taut and supported independently and free of the effective face of said pad, said flexible stencil being adapted, under the pressure of the object being decorated, to yield from the plane of its expanse and compress said elastic pad.

4. Apparatus for use in applying a vitrifiable decoration upon a round object, which apparatus includes in combination a container having a shallow recess, an elastic pad of absorbent material positioned in said recess, said pad being saturated with the material to be applied in liquid state, a flexible stencil drawn taut and supported independently and free of the face of said pad, said flexible stencil being adapted, under pressure produced by the rolling advance of said object thereupon, to yield from the plane of its expanse and to compress said elastic pad on a line advancing with such rolling object.

5. The structure of claim 4, in which the plane of said stencil lies substantially parallel to and at an interval from the effective face of said pad.

6. The structure of claim 4, in which the face of said pad lies outward of the mouth of said recess, and the plane of said stencil lies substantially parallel to and at an interval from the effective face of said pad.

7. Apparatus for use in applying a vitrifiable decoration upon an object, said apparatus including in combination a body adapted to present over an extended surface a quantity of liquid vitrifiable material, and a flexible stencil sheet with open-work pattern drawn taut and supported an interval from said surface, said flexible stencil being adapted to yield from the plane of its extent, under the pressure of the object to be decorated applied to it, and into contact with said liquid-bearing surface, whereby the liquid brought into contact through the interstices of the open-work pattern of the stencil with the surface of the object is transferred in desired pattern to said last-mentioned surface.

8. Apparatus for use in applying a vitrifiable decoration upon an object, said apparatus including in combination a body adapted to present over an extended surface a quantity of liquid vitrifiable material, and a flexible stencil sheet with open-work pattern drawn taut and supported an interval from said surface, said flexible stencil being adapted to yield, under the pressure of the object to be decorated applied to it, and to move so much of the area of the stencil as is engaged immediately beneath the object from the plane of extent of the stencil and into contact with said liquid-bearing surface, whereby the liquid brought into contact through the interstices of the open-work pattern of the stencil with the face of the object is transferred in desired pattern to said face.

9. Apparatus for use in applying a vitrifiable decoration upon an object, said apparatus including in combination a body adapted to present over an extended area a surface flooded with liquid vitrifiable material, and a flexible stencil sheet impervious in main and pervious in pattern drawn

taut and supported an interval from said flooded surface, said flexible stencil being adapted to yield from the plane of its extent, under the pressure of the object to be decorated applied to it, and into contact with said flooded surface, whereby the liquid is applied to the face of said object in desired pattern.

10. Apparatus for use in applying a vitrifiable decoration upon a round object, said apparatus including in combination a body adapted to present over an extended surface a quantity of liquid vitrifiable material, and a flexible stencil sheet with open-work pattern drawn taut and supported an interval from said surface, said flexible stencil being adapted, under the pressure of the object to be decorated rolled thereupon, to yield from the plane of its extent and into contact with said liquid-bearing surface on a line advancing with the rolled object, whereby the liquid brought into contact through the interstices of the open-work pattern of the stencil with the advancing face of the object is progressively transferred in desired pattern to said face.

11. Apparatus for use in applying a vitrifiable decoration upon a round object, said apparatus including in combination a body adapted to present over an extended area a surface flooded with liquid vitrifiable material, and a stencil sheet impervious in main and pervious in pattern drawn

taut and supported an interval from said flooded surface, said flexible stencil being adapted, under the pressure of the object to be decorated rolled thereupon, to yield from the plane of its extent and into contact with the flooded surface on a line advancing with the rolled object.

12. Stencil apparatus comprising a body presenting an extended surface, a flexible stencil sheet drawn taut and lying an interval from said surface, and means for flooding said surface with relatively viscous decorating material.

13. Stencil apparatus comprising a body presenting an extended surface, a flexible stencil sheet drawn taut and lying an interval from said surface, and means for providing said surface with a flooded coating of decorating material, said stencil sheet being adapted over a portion of its area to yield from the plane of its extent and into contact with said flooded coating.

14. Stencil apparatus comprising a body presenting a surface, and a flexible stencil extending adjacent to and lying an interval from said surface, a reservoir containing a liquid pool of decorating material, and means for immersing said surface in said pool, to provide the surface with a coating of decorating material for co-operation with said stencil.

ERNEST M. HOMMEL.
